(57) **CLAIM**

The ornamental design for a rear projection television display, as shown and described.

DESCRIPTION

FIG. 1 is a perspective view of a rear projection television display showing our new design;

FIG. 2 is a front view thereof;

FIG. 3 is a rear view thereof;

FIG. 4 is a right side view thereof;

FIG. 5 is a top plan view thereof; and,

FIG. 6 is an inverted plan view thereof.

The left side view is a mirror image of the right side view shown in FIG. 4.

The broken lines shown in FIGS. 2-4 and 6 are for illustrative purposes only and form no part of the claimed design.
